Patented Jan. 31, 1967

206,803

REMOTE CONTROL UNIT FOR A RECORDING SYSTEM

Wesley L. Kirchoff, Los Angeles, Calif., assignor to Anaplex, Incorporated, Kansas City, Kans., a corporation of Kansas

Filed Oct. 11, 1965, Ser. No. 87,414

Term of patent 14 years

(Cl. D26—13)

FIG. 1 FIG. 2 FIG. 3

FIG. 4 FIG. 5

FIGURE 1 is an elevational view taken from the left side of a remote control unit for a recording system showing my new design;

FIGURE 2 is a front elevational view thereof;

FIGURE 3 is an elevational view taken from the right side thereof;

FIGURE 4 is a bottom plan view thereof; and

FIGURE 5 is a top plan view thereof.

I claim:

The ornamental design for a remote control unit for a recording system, substantially as shown.
